ELECTRIC CABLE SYSTEM AND JOINT
THEREFOR

Fred C. Meyer, Paterson, N. J., assignor to The
Okonite-Callender Cable Company, Incorporated,
Paterson, N. J., a corporation of New Jersey

Application April 27, 1934, Serial No. 722,655

6 Claims. (Cl. 247—3)

This invention is directed to an improvement in semi-stop joints which are particularly adapted for use in cable systems wherein a plurality of insulated but unsheathed cable conductors are enclosed in a pipe line filled with oil under pressure which may be as high as two hundred and fifty pounds or even higher, the pipe line being of large internal diameter to permit of relative movement of the insulated conductors so that "snaking" of the conductors can take place without detrimentally affecting the installation.

One of the objects of the invention is the provision of a semi-stop joint construction in which the necessity for piping exterior to the joint is eliminated.

Another object of the invention is the provision of means for separating or isolating the oil in sections of the pipe line.

A further object of the invention is the provision of a joint which permits of drawing the oil from any section of the line desired, for the purpose of repairs, inspection, renewals, etc., without the necessity of draining the oil from any other section.

A still further object of the invention is the provision of a construction in which the joint structure is such as to provide a stiffener structure between the pipe lines which are united by the joint.

A still further object of the invention is the provision of a joint construction which permits of pipe expansion and contraction due to thermal conditions.

In the accompanying drawing:

Fig. 1 is a longitudinal sectional view of a joint constructed in accordance with the invention, the section being taken on the line 1—1 of Fig. 2;

Fig. 2 is a cross section of the joint of Fig. 1 taken on the line 2—2 of said figure; and

Fig. 3 is a longitudinal view of a modified joint. Referring to the drawing in detail and first of all to the embodiment illustrated in Figs. 1 and 2, A and B designate the adjacent ends of the cable pipe line in which the cable is to be installed. This pipe line which may be of any suitable material, metal fiber, etc. capable of holding pressure, is of relatively large internal diameter so that the cable conductors can be readily drawn thereinto and so that relative movement will be permitted between the several insulated conductors composing the cable thereby providing for "snaking" of the cable conductors when the cable is placed in service.

The ends of the pipe lines are provided with increasers 1 and 2 belled at their inner ends as

shown at 3 and 4. These increasers may be welded, for example, to the ends of the pipe line. If desired, the increasers may be dispensed with and the ends of the pipes belled instead.

For purposes of illustration I have shown a 5 three conductor cable, the conductors of which are designated 5.

Each conductor is individually insulated with oil impregnated insulation 6, paper tape, for example, wrapped about the conductor. In addition to the insulation 6 each conductor is provided with electrostatic shielding tape 7, such as a thin copper tape wrapped spirally about the insulation.

In practice the cable conductors made up as 15 above described are enclosed in a temporary lead sheath for shipment to the installation. In drawing the cable conductors into the pipe line the temporary lead sheath is removed as will be brought out hereinafter.

8 designates the enclosing casing of the joint within which the cable conductors are to be joined.

Within the joint casing 8 adjacent each end thereof are barrier plates 11 of non-magnetic material such as bronze extending transversely of the casing and bolted rigidly to the upset ends of the increasers 1 and 2 by bolts 12. Each of these barrier plates is provided with thimbles 13 for receiving the cable conductors, the bore in each of the thimbles being slightly tapered as shown.

In making up the joint a wrapping 14, surgical webbing, for instance, or any non-magnetic material either fibrous or metallic, is applied immediately about the short sheath length 9 which is left about each conductor, the remainder of each temporary lead sheath being removed as the conductors are drawn into the pipe line. This wrapping is applied spirally about the lead with a half lap and the conductor so prepared is jammed into the tapered thimbles of the barrier plates 11, thus providing a wedge type seal holding the wrapping in its proper position and thus reinforcing the sheath at this point.

The sheath lengths 9 offer high resistance to oil flow from one side of the barrier plates to the other. The length of these sections depends on the pressure used and requirements to be met, but in any event it will be appreciated that the longer the lengths the more effective they are in reducing oil flow.

The ends of the cable conductors are brought together and joined as shown at 15 intermediate the barrier plates 11 and then wrapped with var- 55

nished cambric and paper tape 16. Finally copper braid 17 is wrapped about the varnished cambric and paper tape and each end soldered to the wipe joints 18 which connect the ends of the short sheath lengths 9 and thimbles 13. When the wrapping 14 is of fibrous material it is terminated short of the forward end of each of the thimbles 13, so as to permit the wipe joints 18 to be made. These wipe joints provide an oil proof joint against flow of oil out of the joint casing 8 into the cable and from thence to the pipe line, there being only a slight seepage through the insulation and strands of the conductor.

As thus far described it will be appreciated that lengths of sheath 9 just long enough to wipe to the thimbles 13 would be effective as a stop feature and any additional length of these sleeves reduces the oil flow, the greater the length the less the oil flow. A condition might arise, however, where there is an oil flow from the joint casing through the cable insulation and the conductor strands to the pipe line, in which event a tensional stress is set up in the sheath lengths or sleeves 9, likely to cause rupture particularly close to the barrier plates. This condition is taken care of in the present construction by the wrapping 14.

The enclosing casing 8 of the joint overlaps the ends of the increasers 1 and 2. The joint casing at each end is provided with an outwardly extending annular flange 19 rigid therewith while the belled ends 3 and 4 of the increasers 1 and 2 are provided with a loose ring 20. A lead tipped gasket 21 is interposed between each of the rings 20, the increasers 1 and 2 and the end of the enclosing joint casing 8. Bolts 22 serve to draw up the rings 20 to provide a liquid tight joint between the joint casing and the pipe increasers 3 and 4.

The cable pipe line is kept filled with oil 24 under sufficiently high pressure to increase the dielectric strength of the oil, for example, from five atmospheres upwards and inasmuch as communication is desired between the interior of the joint casing 8 and the cable pipe line, while avoiding piping exterior to the joint, I provide, at each end of the joint a valve-controlled pipe 23. These pipes lie wholly within the joint casing and pipe line. The valves controlling these pipes may be hand operated or automatic and will be closed either manually or automatically in the event of a leak in the system.

It will be seen from the foregoing that this structure eliminates the necessity of external piping for maintaining communication between the interior of the joint casing and the pipe line. If desired, stiffener rods, such as shown at SR fastened to the barrier plates 11 may be provided within the joint casing to prevent the ends of the pipe line from working in and out relatively to the joint casing.

It will be seen in addition to all of the foregoing that my improved construction provides the following advantages. In the event repairs have to be made to any cable length intermediate two joints it is merely necessary to drain the joint and the section of pipe line containing the cable to which access is desired. The joint casing 8 could then be slipped to one side, the barrier plate thus exposed removed and the cable withdrawn and another section pulled in without disturbing any of the rest of the line at all. So that here I have a joint for "buried in the ground" cable systems which necessitates merely uncou-

ering a joint for the purpose of obtaining access to a cable section, thus avoiding the trouble and expense of uncovering an entire length of cable which has been necessary heretofore with "buried in the ground" cable systems. If manholes are erected with this type of construction not only do I obtain the advantages of present day conduit constructions but the advantages of a "buried in the ground" system.

While I have described a construction in which the sheathed lengths 9 have been left on the cable at the barrier plates 11, it is to be understood that if desired packing glands may be substituted for these sheath lengths.

In the embodiment of my invention illustrated in Fig. 3 I provide barrier plates 11, each equipped with thimbles 13 for receiving the cable conductors. The increasers 1 and 2 of Fig. 1 are done away with, and instead of securing the barrier plates to these increasers, I provide the barrier plates with a large diameter sleeve-like rearward extension 11', these extensions being telescoped by the joint casing 8. The extensions 11' where they project from the joint casing are materially reduced in diameter to provide offset or eccentric sleeves 25 of the same diameter as the pipe lines and in alignment therewith. These eccentric sleeves or extensions terminate short of the ends of the pipe line to leave a gap 26.

Each of the eccentric sleeves 25 of the barrier plates is provided with a ring 27 and surrounding the adjacent end of the pipe line lengths to be joined is a ring 28. Between these two rings 27 and 28 and surrounding the eccentric sleeve 25 of the barrier plates as well as the cable pipe line is a sleeve 29. Lead tipped gaskets 30 are interposed between the ends of the sleeve 29 and the rings 27 and 28 and the sleeve-like extension 25 of the barrier plate and cable pipe line.

Bolts 31 connect the rings 27 and 28, and when these bolts are drawn up a liquid-tight joint is provided between the ends of the extension of the barrier plates and the cable pipe line. This provides a construction permitting of a certain amount of expansion of the cable pipe line relatively to the extension of the barrier plates to compensate for a certain amount of settling of the pipe line after being buried in the ground and to compensate for any expansion and contraction of the pipe line due to thermal conditions without necessitating movement of the barrier plates.

The joint casing 8 as above mentioned telescopes the extensions 11' of the barrier plates.

32 designates a ring surrounding and secured to the joint casing 8 adjacent each end thereof. 33 designates a loose ring similar to the ring 20 of Fig. 1 surrounding each barrier plate extension 11'. A lead tipped gasket 34 is interposed between the ring 33, the end of the joint casing 8 and the extension 11' of the barrier plate so that when the bolts 35 connecting the rings 32 and 33 are set up a liquid tight joint is provided between the end of the joint casing and the barrier plate. By providing the large diameter extensions or sleeves 11' it will be appreciated enough friction will be provided to prevent detrimental relative movement between the barrier plates and joint casing, and by providing the reduced diameter sleeves 25 which terminate short of the pipe line movement of the pipe line is permitted without transmitting this movement to the joint.

To maintain communication between the in-

terior of the joint casing 8 and of the cable pipe line and yet eliminate the necessity of external piping, I provide a valve 36 in each of the barrier plates 11, the valve stems lying within the sleeves 11', the valve stems projecting from the offset between the sleeves 11' and 25 so as to be accessible for adjustment if desired or necessary. These valves 36 may be flow operated or otherwise automatically operated if desired.

10 It will be understood that the cable conductors in this embodiment of my invention may be joined in the same manner as in Fig. 1 and that the thimbles 13 in the barrier plates will be wiped to the short sheath lengths 9.

15 In this embodiment of my invention, therefore, I have eliminated all external piping, provided for stiffening the joint so that the barrier plates 11 will remain at a fixed distance apart, and at the same time provided for a certain 20 amount of movement of the pipe line relatively to the joint, due to settling and thermal conditions without transmitting such movement to a detrimental extent to the joint.

What I claim is:—

25 1. In combination a joint casing for high tension electric cable systems, a barrier plate within said joint casing adjacent each end thereof, a pipe line filled with oil maintained under high pressure, insulated cable conductors in said pipe line, means for rigidly connecting said barrier plates to the adjacent ends of two lengths of the pipe line, thimbles for said barrier plates for receiving said cable conductors, the cable conductors extending through said thimbles into 30 the interior of the joint casing, means for joining the ends of the conductors within said joint casing, each of said cable conductors being provided with a short length of an impervious metal sheath surrounding the insulation of the conductors 35 and extending through said thimbles, a non-metallic wrapping about that portion of each impervious metal sheath which extends through a thimble, a wiped joint uniting each of said thimbles with the metal sheath of the conductor 40 passing through that thimble, oil under high pressure filling the cable pipe line and oil under the same pressure filling the joint casing.

2. In combination a joint casing, barrier plates within the joint casing adjacent each end thereof, a cable pipe line, said barrier plates being sealed to said pipe line, insulated cable conductors in said pipe line, means for connecting each end of the joint casing to the cable pipe line liquid tight, thimbles for said barrier plates, 50 each of said conductors being provided with a short length of lead sheath about the insulation thereof, a non-magnetic material about the short length of lead sheath of each conductor, the lead sheathed portion of each conductor extending through a thimble of said barrier plates into the interior of said joint casing, means for joining the adjacent ends of the conductors within said joint casing, a wiped joint for uniting each thimble with the lead sheath of its conductor, oil under high pressure filling the pipe line and oil under the same pressure filling the 55 said joint casing, and an enclosed valve controlled pipe extending from the pipe line through each of said barrier plates and terminating within the joint casing to maintain communication 60 between the interior of the joint casing and of said cable pipe line.

3. In combination a joint casing, barrier plates within the joint casing adjacent each end thereof, 75 a cable pipe line, insulated cable conductors in

said pipe line, means for connecting each end of the joint casing to the cable pipe line liquid tight, thimbles for said barrier plates, each of said conductors being provided with a short length of lead sheath about the insulation thereof, a fibrous material about the short length of lead sheath of each conductor, the lead sheathed portion of each conductor extending through a thimble of said barrier plates into the interior of said joint casing the fibrous material extending into the thimble and terminating short of the forward end thereof, means for joining the adjacent ends of the conductors within said joint casing, a wiped joint for uniting each thimble with the lead sheath of its conductor, oil under high pressure filling the pipe line and oil under the same pressure filling the said joint casing, and an enclosed valve controlled pipe extending from the pipe line through each of said barrier plates and terminating within the joint casing to maintain communication between the interior of the joint casing and of said cable pipe line.

4. A joint for high tension electric cable systems of the type in which the insulated cable conductors are laid in a pipe line of sufficiently large diameter to permit of free relative movement of the insulated conductors, the pipe being filled with oil maintained under high pressure, said joint comprising in combination an enclosing joint casing within which the conductors are to be joined, a barrier within the joint casing at each end thereof, and rigidly attached to the ends of adjacent pipe sections and overlapped by the joint casing, thimbles integral with said barriers, each of said thimbles having a tapered bore, an insulated cable conductor passing through each of said thimbles to the interior of the joint casing for joining within the casing, that portion of each conductor passing through said thimbles being provided about its insulation with a short length of lead sheath and with fabric wrapped about said sheath, insulation about the joint of the cable conductors, a metal covering about the last mentioned insulation, said metal covering, the lead sheath and said thimbles being connected by wipe joints, a flange adjacent each end of the joint casing and rigid therewith, a ring loosely surrounding each of said pipe sections, packing between the said rings, the pipe sections and the ends of the joint casing, and bolts connecting said flanges and rings whereby a liquid-tight joint is provided between each end of the joint casing and the cable pipe, oil filling the joint casing and a valve controlled pipe at each end of the joint lying within the pipe line and passing through said barrier plates and terminating within the joint casing, whereby the oil within the joint casing is maintained at the same high pressure as the oil within the pipe line.

5. A joint for high tension electric cable systems of the type in which the insulated cable conductors are laid in a pipe line of sufficiently large diameter to permit of free relative movement of the insulated conductors, the pipe line being filled with oil under high pressure, said joint comprising in combination an enclosing joint casing, barrier plates within the casing adjacent the ends thereof, means for rigidly connecting the barrier plates to the ends of the pipe line, and a pipe passing through the barrier plates and enclosed by the joint casing and pipe line and terminating within the casing for

maintaining communication between the joint casing and pipe line.

- 5 6. In combination a pipe line filled with oil maintained under high pressure, a joint in the pipe line, said joint comprising a joint casing the ends of which are secured liquid-tight to the pipe line, barrier plates within the joint casing secured to the ends of the pipe line, stiffening members within said joint casing secured to said barrier plates and extending from 10 the barrier plates at one end of the casing to

the barrier plates at the opposite end of the casing, insulated cable conductors passing liquid-tight through said barrier plates and spliced to each other within said casing, and valve controlled pipes terminating within the joint casing for maintaining communication between the pipe line and the interior of the joint casing whereby the joint casing is kept filled with oil at the same pressure as the oil in the pipe line.

5 10

FRED C. MEYER.
